(57) **CLAIM**

I claim the ornamental design for a straw fireman's hat, as shown and described.

DESCRIPTION

FIG. 1 is a front view of a straw fireman's hat of the present invention;

FIG. 2 is a right side view of the straw fireman's hat of FIG. 1; and,

FIG. 3 is a top side view of the straw fireman's hat of FIG. 1.

1 Claim, 3 Drawing Sheets

FIG. 1

FIG. 2

FIG. 3
